UNITED STATES PATENT OFFICE.

HOWARD LACY, OF CARSHALTON, ENGLAND.

PROPELLED TORPEDO.

No. 895,870.

Specification of Letters Patent.

Patented Aug. 11, 1908.

Application filed July 26, 1907. Serial No. 385,749.

To all whom it may concern:

Be it known that I, HOWARD LACY, a subject of the King of Great Britain, residing at Kelvin, Camden Road, Carshalton, in the county of Surrey, England, engineer, have invented certain new and useful Improvements in and Relating to Propelled Torpedoes, of which the following is a specification.

This invention is designed by the placing 10 of powerful magnets shaped to conform with the bow of any type of torpedo now used in naval operations to constitute what may be termed a magnetic torpedo. The object being to utilize "magnetic forces" to direct the 15 torpedo against the hull of iron or steel vessels. These magnetic torpedoes are suitable:—first, as an improved means of attack by providing greater accuracy of shot, whether the target be moving or stationary; second, as a 20 means of harbor defense, each individual torpedo being capable of covering more given area in a harbor than is possible by any present method of using mines or torpedoes; third, as a means of countermanning, and 25 clearing a harbor defended by the enemies' mines or torpedoes.

The application of these powerful magnets in the bows of torpedoes can be effected by connection with a source of electrical power 30 on shore or on board a vessel or with storage batteries located within the torpedoes themselves—whether those torpedoes be of spar type—the uncontrolled type—the controlled type which type again may be subdivided as 35 the mechanically and the electrically controlled torpedoes.

Torpedoes are definitely assigned two distinct functions in warfare:—first, as the armaments of ships and boats; second, as 40 forming part of the submarine harbor defenses—but with the addition of magnets a third function becomes possible viz:—as a method of countermanning and attacking the harbor of an enemy.

The force of attraction produced by magnetism is a great deal more powerful than is ordinarily supposed—and the more heavily armored and powerful the vessel the greater the force of attraction exerted. All vessels 50 of iron or steel constitute in themselves very powerful magnets and their magnetic attraction serves to enhance the effective force of the electro magnet contained within the torpedo directed against it. The torpedo furnished as described when traveling towards an object of attack is easily diverted from its

normal course and the "inherent directive force" within the field of the electro-magnet as it nears an iron or steel vessel increases and its accuracy of direction with reference to the 60 position of the object as well as the "speed" and "range" are greatly augmented.

When the mass forming the target is moving on a course parallel to a vessel discharging the torpedo and moving in the opposite direction certain causes of deflection arise and consequent error in aim is liable to arise and involves intricate calculation to avoid it. Again assuming the object-mass and the discharging vessel to be traveling on a parallel 70 course in the same direction but not at the same speed similarly intricate calculation is necessary to avoid error.

With the aid of this invention the chances of error are reduced owing to the attraction 75 of the object-mass for the magnetic field of the magnet in the bow of the torpedo and the influence exerted thereby to bring the two bodies into collision operates strongly in aid of the attainment of correctness of aim be- 80 sides the saving of time and facility for more rapid launching. The error of aim when launching naturally becomes enhanced as the distance increases, while the influence of the object-mass becomes the stronger in at- 85 tracting the torpedo back to the correct path the nearer those two bodies approach.

I place within the bow end of a torpedo an electro-magnet of the construction herein-after mentioned and of a contour conforming 90 to the internal shape of said bow for a double purpose. A primary object in view is that when a torpedo has been aimed and is running somewhere wide of the object it is designed to strike (say an iron or steel vessel) to utilize the magnetic attractive force exerted by such iron or steel mass to correct the course followed and obtain the desired effect, and when such deviation has been rectified and the torpedo has been brought into contact 100 with the object, to retain it in such contact until such time has arrived, as may to those directing the operations seem fit, for causing the destructive explosion. The combined, or contending forces of propulsion and mag- 105 netic attraction are thus utilized to attain the desired arrival of the torpedo at its destination.

Figure 1 shows in plan view a portion of the bow of a torpedo shell. Fig. 2 is a front view of the pair of coned ends of the electro magnets seen in Fig. 1. Fig. 3 is a sectional

diagrammatic plan view to an enlarged scale of the front or coned end of one of the electro-magnets and of a part of the rear end of the same the middle portion being broken away for convenience of the drawing. Fig. 4 is a similar sectional diagrammatic view to Fig. 3 of the magnet but taken near the rear end of the same.

In Figs. 3 and 4 the winding is assumed to have been carried as far only as the third sized wire.

a indicates the core, *b* the spreaders, *c* the diamagnetic plates, *d* the cones, *e* the first or coarsest layers of winding, *f* the next or medium layers in thickness, *g* the finest and outermost layers, *h* the insulating material layered between each layer of winding, *i* is the yoke.

In Fig. 1 where four different sizes of wire are assumed to be wound, 1, 3, 5 and 7, indicate the beginnings or ingoings of the respective thicknesses of wire winding and 2, 4, 6 and 8, indicate respectively the corresponding outcomings or endings of each thickness of wire.

To construct an electro magnet for above said purpose a core is assembled as follows:—

Core.—Two bundles of soft iron wires are taken and cut to even lengths. On the ends intended for the "back" of the electro magnet spreaders are clamped on each of the bundles of soft iron wire such as by means of hydraulic pressure or shrinkage after heating. One end of each bundle *a* of iron wire passes through the center of a spreader *b* and is faced up flush with the same. The outside diameter of these spreaders *b* is preferably twice that of the bundle of iron wire over which it is firmly clamped.

Plates c, c.—After each bundle has had its respective spreader *b* firmly clamped upon it a plate *c* of diamagnetic material of either brass, copper, or aluminium formed with a hole in the center large enough to enable the plate *c* to be easily slipped on to the bundle and it is placed in metallic contact with the spreader *b*. These diamagnetic plates *c* should have an outside diameter large enough to hold the helices of superimposed insulated wires of high electrical conductivity which are to be wound on these cores, *a*, *a*.

Cones, d.—On the other end of each bundle *a* of soft iron wire which is intended for the front end of the electro-magnet are now shrunk, either by means of hydraulic pressure, heating, or like means, and firmly fixed cones of soft wrought iron, proportioned as follows as nearly as possible to suit the build of torpedo within which this form of electro-magnet is to be placed. The base 10 of each cone *d* in diameter should equal the diameter of the bundle of iron wire plus a thickness of material left after having bored out the base of the cone to a depth sufficient to firmly hold the core *a* in fibrous contact.

Having bored out the cones *d* they are fixed firmly by means of hydraulic or like means—each on its own bundle of wire. The lengths of the cones *d* are each governed by the length of the bundle of soft iron wire to which it is attached as follows:—taking half the length of the bundle *a* as the total length of the cone. The diameter of cone *d* where it is clamped to the bundle of iron wire is used as the base 10 of a triangle one side of which is at right angles to the base, and along this side the above length is measured. The other side of the cone *d* or triangle is formed by starting the opposite point on the cone base line and drawing a line to the point measured on the straight side making its length. A piece is now cut off from the apex of each cone at right angles to their length so that the diameter of the section obtained is about $\frac{1}{3}$ to $\frac{1}{2}$ an inch. The two bundles of soft iron wire *a* with spreaders *b* and diamagnetic plates *c* at the back ends and each with a cone of equal length on the front ends are yoked together at the back end by a soft iron yoke *i* having a dimension in square inches equal to one half the length of one of the bundles of wire *a* and this may be made more clear as follows:—Multiply the outside diameter of one of the spreaders *b* by the said half-length which will make the number of square inches required: as an example suppose spreader to equal 2" and length of iron wire bundle is 30 inches the half this being 15". Then the yoke adapted thereto should be 15 square inches, we have 2" for width, multiplied by $7\frac{1}{2}$ = 15, and yoke is therefore 2" wide and $7\frac{1}{2}$ " long.

When fixing the yoke *i* on the spreaders *b* of the two bundles of soft iron wire *a* the straight sides of the cones *d* should be parallel and facing each other inside. The yoke is fastened on the spreaders by studs set in the spreaders and nuts holding the yoke on firmly to the face of the spreaders; the joints being water-tight and as mechanically perfect as possible.

The winding.—After the cores have been insulated by a wrapping of tape and shellac, or similar means the winding of the helices are started on one bundle right handed and on the other left handed. The helix on each core is constructed with four or more different sized wires. Although in Figs. 3 and 4 this construction is only carried as far as the completion of the third thickness and the order of placing them on should be to wind the first two layers on each core with the heaviest of the four or more different sized wires chosen; then the next smaller size for four more layers, then the next size smaller (than to that with which the last four layers were wound) is taken and wound on for six layers, and if only four sizes of insulated wire are to be used to form the helix on each

core the smallest size of the four is utilized with which to wind on eight layers, making a total of twenty layers of graduated sizes of insulated wire commencing with the heaviest size next to the core and finishing with the finest size of the wires chosen on the outside of each helix. Another feature of this winding is that each layer of wire wound is carefully insulated from its neighboring layer by shellac and paper or similar means. Another feature is that the beginnings and ends of each of the different sized insulated high conducting wires forming the helix is brought out through holes in the diamagnetic plates at back end of magnet to enable combinations to be made as follows:—series, multiple, series multiple, multiple series, multiple-series-series-multiple, shunt series, shunt-multiple, shunt-multiple-series, shunt-series-multiple, and so on; the more wires the more combinations so that the electro-magnet can be adjusted to have effective power according to the electric current produced and utilized from a source of supply. Another feature of this winding of the helices on the cores is that the direction of the winding of the wire round the core is reversed at the end of every second layer. The first wire *e* wound on the core being the heaviest is wound on for two layers, say right handed, then taking the second sized wire *f* the direction of the winding for the first two layers of this size are wound on left handed and after these two layers are on and this same sized wire is turned back on itself and the next two layers are wound on right handed. Taking now the third sized wire *g* the winding is started in left handed direction for two layers. Then the wire is turned back on itself and two layers wound on in right handed direction, the same sized wire is then turned back on itself again and two more layers are wound on left handed. Taking now the fourth sized wire not shown on Figs. 3 and 4 the winding is put on for two layers right handed. Then turning back this wire on itself wind on two layers left handed, again turning back the wire on itself wind on two layers right handed and finally turning back the wire on itself reversing the direction of winding for this size, for the third time two more layers are wound on left handed; all these layers are to be carefully insulated from each other and the beginnings 1, 3, 5, 7, and ends 2, 4, 6, 8, see Fig. 1, of the four sizes of wire are brought out free of the windings or helix for the purpose above stated. Another feature of this winding is that the first two layers *e* next to the core *a* of the heaviest size wire (of the four sizes chosen) are wound on the length of the core *a* extending from the diamagnetic plate *c* to the juncture of the cone *d* with the bundle of soft iron wire *a*. The first layer of the second sized wire *f* is wound on from the diamagnetic

plate *c* along the whole length of the cone *d* of soft iron wire and continued out along the cone to a point within one inch of where the cone was cut off (at 12) and from this point the fourth layer of the magnet is wound on continuously back to the diamagnetic plate *c*. The fifth layer is wound on over the last layer beginning at the diamagnetic plate out to a point on the cone within an inch of where the third and fourth layer of the magnet extended; the sixth layer is wound back from this point back to the diamagnetic plate, the seventh layer is wound from the diamagnetic plate out to a point within an inch of the point on the cone where the fifth and sixth ended and began, and the eighth layer from this point back to the diamagnetic plate; the ninth and tenth layers are wound on from the diamagnetic plate to within an inch of where the seventh and eighth extended on the cone, and so on, shortening the length of the layers till this shortening brings the layers equal in length to that length which obtained in the first two layers on the core. This shortening of the layers also depends on the form of the bow within which the electro-magnet is to be placed, and the form and shape of the cones are changed to meet each particular case; either by lengthening the distance of the windings along the cone for the different layers and this making the outward form of the cone more obtuse or by shortening the distance the windings extend along the cone of the different layers with relation to each other, and thus making the outward form of the finished electro magnet with a cone more acute in form.

Having now particularly described and ascertained the nature of my said invention and in what manner the same is to be performed, I declare that what I claim is:—

1. The combination with a torpedo, of a magnet mounted in the bow or nose thereof for insuring collision between the torpedo, and a vessel or other object, comprising a core and a set of superposed layers of windings arranged thereon, the axial lengths of the several layers decreasing progressively at one end of the core to form a helix that conforms substantially to the contour of the torpedo nose.

2. The combination with a torpedo, of a magnet mounted in the bow or nose thereof for insuring collision between the torpedo, and a vessel or other object, comprising a core of soft iron wire, a soft iron cone inclosing the core at one end and firmly secured thereon, the apex of the cone projecting into the nose of the torpedo, and a helix composed of a plurality of superposed layers of wire surrounding the core and the cone thereon.

3. The combination with a torpedo, of a magnet mounted in the bow or nose thereof comprising a core, and a set of superposed

layers of wire wound thereon, the axial lengths of the layers decreasing progressively at one end of the core, and the size of the wire decreasing correspondingly with the decrease 5 in axial length of the respective layers.

4. The combination with a torpedo, of a magnet mounted in the bow or nose thereof, comprising a core, extension pole pieces thereon conforming in shape to the nose of 10 the torpedo, and layers of wire wound on the core, the wire of the several layers diminishing in size from the core outwards and correspondingly increasing in the number of 15 layers for each sized wire, such windings being reversed at the end of each second layer, and the ends of the wire composing each winding being brought to the exterior

of the magnet to enable the several windings to be connected up in different combinations with a source of current supply whereby the 20 strength of the magnet may be varied, layers of insulating material interposed between each layer of wire, a spreader clamped on the rear end of the core, and a diamagnetic plate positioned by the said spreader and serving 25 to retain the windings of wire in place.

In testimony whereof I have hereunto set my hand in presence of two subscribing witnesses.

HOWARD LACY.
